UNITED STATES PATENT OFFICE.

HARRY J. WILLIAMS, OF BROOKLYN, NEW YORK, ASSIGNOR TO EDWARD ERMOULD CO., OF NEW YORK, N. Y., A CORPORATION OF NEW YORK.

LABELING MACHINE.

Application filed June 21, 1924. Serial No. 721,406.

To all whom it may concern:

Be it known that I, HARRY J. WILLIAMS, a citizen of the United States, and a resident of Brooklyn, in the county of Kings and 5 State of New York, have invented certain new and useful Improvements in Labeling Machines, of which the following is a specification.

This invention relates to improvements in 10 labeling machines, more particularly to a picker mechanism for transferring labels from label boxes to articles to be labeled, and the objects of the invention are to improve the picker mechanism so that it will 15 act in conjunction with a paste roller and a grip finger to apply paste to the entire surface of the label so that it will stick throughout its entire surface area when applied to an article to be labeled.

20 To the accomplishment of the above objects and to such others as may hereinafter appear the invention comprises one or more supplemental pickers arranged to close the space between the picker faces of the pickers, so that the pickers and supplemental pickers will receive a layer of paste from the 25 paste roller that will entirely cover the bottom surface of the label as it is removed from the label box, means are also provided for opening the supplemental pickers so that the grip finger can force the label into engagement with the article to be labeled, and as the pickers and supplemental pickers are 30 removed wipers act to wipe the label on the article to be labeled so that the label will stick throughout its entire surface.

The practical adaptation of this invention to a labeling machine, in one form of its embodiment, is illustrated in the drawings, 35 wherein—

Figure 1 is a side view of a machine with parts broken away equipped with picker mechanism made in accordance with the present invention.

40 Figure 2 is a front view of the machine shown in Fig. 1.

Figure 3 is an enlarged detail view on the line 3—3 of Fig. 2 showing the rest and supplemental pickers with associated parts.

45 Figure 4 is an enlarged detail view on the line 4—4 of Fig. 3.

The present invention is to be described in connection with the labeling machine shown in Edward Ermold Patent No. 1,023,143,

5 patented April 16, 1912; it is to be understood, however, that the present invention is equally applicable in a similar way to a variety of machines of this type.

In the drawings 1 designates the frame of the machine to the front of which is secured a plate 20 to which is secured one end of a bracket 21, to the other end of which is adjustably secured a rest 22 for cans, bottles or similar articles to be labeled. The rest in the present instance is arranged to removably hold a small rectangular can *a* suitable plates *b* and *c* secured to the top of the rest being provided for centering the can.

A suitable label box, in the present instance one in number, is provided and is 70 supported in the upper part of the frame of the machine above said rest upon inclined rods 25. The label box is provided with label fingers 4, the lower ends of which are provided with lips 42 for holding a pile of 75 labels 43. The labels are forced downward by means of a weight 45 engaged by a rod 47 which is supported in a guide 48. The guide 48 is secured to an arm 49 mounted on the frame of the machine.

80 Suitable pickers 52 are provided, the inner ends of which are secured to a sleeve 53, loosely mounted upon a shaft 54 secured to the frame of the machine. The top surfaces of the outer ends of the pickers are provided 85 with raised portions or picker faces 61 to which paste is applied for engaging the edges of the bottom label to remove them from the label box. Suitable means, not shown, but shown and described in the above 90 referred to patent, are provided for swinging the outer end of the pickers into engagement with the bottom label in the pile of labels 43 and transferring the same to the article to be labeled on the rest 22.

95 A suitable paste roller 63 is provided which is pivoted to arms 64 mounted upon a shaft 65 secured to the top of the frame of the machine. The paste roller is arranged to move inward along the raised portions or picker faces 61 of the pickers, to coat them with a layer of paste, during the upward movement of said pickers, the paste roller on its inward movement being arranged to engage a roller 72 rotating in a paste box 73 mounted in the frame of the machine. Suitable means, not shown, but shown and described in the above referred to patent, are 100 105

provided for swinging the paste roller into engagement with the pickers and into engagement with the paste box roller.

A suitable grip finger 86 is provided for holding the labels in position on the article to be labeled after the pickers have moved to their lower position with a label removed from the label box. In the present instance the grip-finger is provided at one end with a presser finger 87 for holding the label in position on the article to be labeled, while the other end of the grip-finger is secured to one end of an arm 92 at right angles to the grip finger, the other end of said arm being secured to one end of a shaft 93 rotatably mounted on the frame of the machine. Suitable means, not shown, but shown and described in the above referred patent, are provided for swinging the grip finger into engagement with the label and holding it on the article to be labeled as the label is presented to the article to be labeled by the pickers.

Suitable wipers 109 comprising yielding rubber plates, are provided for wiping the label on the article to be labeled. In the present instance the wipers are secured in holders 110 pivoted to the ends of crank arms 111 which are pivoted to a yoke plate 112 by means of studs 113. The other ends 115 of the crank arms are pivotally connected to the upper ends of links 116 the lower ends of which are pivoted to a vertical slide 117. Suitable means, not shown, but shown and described in the above referred to patent, are provided for operating the wipers to wipe the label on the article to be labeled as soon as the same has been engaged by the grip finger and the pickers have moved upward.

From the above description it will be seen that labels removed from the label box and applied to an article to be labeled will only be attached at the ends or sides of the label and not at the center. In some cases this is a disadvantage. Where, for example, the labeled surface is flat the label is inclined to pucker at the center where it is not glued, making the label unsightly and easily torn.

In the present instance and in accordance with the present invention, the space between the outer ends of the adjacent picker faces 61 of the pickers 52 is closed by means of one or more supplemental pickers *d* having picker faces *e*. The supplemental pickers *d* are each provided with bearing lugs *f* corresponding with similar bearing lugs *g*, secured in suitable recesses situated in the adjacent sides of the pickers 52. The bearing lugs *f* are secured in each instance to a cam shaft *h* which passes loosely through the bearing lugs *g*. The cam shafts *h* are each provided with a follower *i* each of which is arranged to slidably engage a curved cam slide *j*, the lower ends

of which are secured to the rear end of the rest 22 by means of bolts *k*. The followers *i* are kept into engagement with the cam slides *j* by means of spiral springs *l* each of which is mounted on its corresponding cam shaft *h*. The springs *l* act to close the supplemental pickers, as shown in dotted lines in Fig. 4, when the pickers have been moved upward above the cam slides *j* the upper ends of which are rounded as shown at *m* to open the supplemental pickers toward the end of their downward movement.

From the above description it will be seen that when in the operation of the machine the pickers 52 move upward, from the position shown in Fig. 2, the supplemental pickers *d* will remain in open position due to the action of the cam slides *j* until the supplemental pickers have passed beyond the ends of the cam slides; however, before this point is reached the wipers 109 will have acted to wipe the label on the article to be labeled, on the rest, and the grip finger 86 will have moved upward out of the way.

In the further upward movement of the pickers 52 and as soon as the cam slides *j* have permitted the supplemental pickers *d* to close, the paste roller 63 moves inward from its outward position and rolls over the picker faces 61 of the pickers and the picker faces *e* of the supplemental pickers, so as to coat them with a layer of paste. On the further upward movement of the pickers the same together with the supplemental pickers engage the bottom label in the label box to completely cover the same with paste.

On the downward movement of the pickers, with the bottom label withdrawn from the pile of labels, the cams *i* of the supplemental pickers *d* engage the rounded ends *m* of the cam slides *j* acting against the springs *l* to open the supplemental pickers, releasing the central portion of the label, now coated with paste, and free to be engaged by the grip finger 86 and forced into engagement with the article to be labeled as the pickers 52 reach their lower position as shown in Fig. 2.

In the further operation of the machine, from the position shown in Figure 2, the pickers 52 with the supplemental pickers *d* in open position, move upward to release the label now held by the grip finger 86 in position on the article to be labeled, so as to permit the wipers 109 to wipe the label.

The cam slides *j* are made of sufficient length so that on the upward movement of the pickers the supplement pickers will remain open a sufficient period of time to permit the grip finger to be removed after the wipers have completed or nearly completed their wiping operation. It is of

course obvious that the supplemental pickers must be open to permit the grip finger to move either into position to engage the label or out of position to disengage the label and 5 that the supplemental pickers must be closed to receive a coating of paste and until a label has been removed from the bottom of the pile of labels.

10 The provision of the supplemental pickers as above described provides means for coating the entire surface of a label and applying it to an article to be labeled so that it will stick throughout its entire surface which is a great advantage in many instances and much to be preferred where the 15 label is only pasted at the sides or ends leaving the center or unpasted portion to buckle and tear.

10 It is of course obvious that in place of two supplemental pickers only one can be used by making it of sufficient width to close the space between the pickers in which instance only one cam slide will be required.

25 While the invention has been described with particular reference to details of construction, the same is not to be considered as limited thereto, as many changes can be made and still fall within the scope of the invention set forth in the following claims,

30 What I claim is:—

1. A labeling machine comprising in combination a rest for holding articles to be labeled, a label box, pickers spaced apart for removing labels from said label box to 35 articles to be labeled on said rest, supplemental picker means, means for hinging said supplemental picker means to the adjacent sides of said pickers to close the space between the pickers and means for independently opening and closing said supplemental picker means.

40 2. A labeling machine comprising in combination a rest for holding articles to be labeled, a label box, pickers spaced apart for removing labels from said label box to 45 articles to be labeled on said rest, supplemental picker means arranged to close the space between said pickers, a paste roller for applying paste to said pickers and said supplemental pickers, a grip finger and means for opening and closing said supplemental pickers,

50 3. A labeling machine comprising in combination a rest for holding articles to be

labeled, a label box, pickers spaced apart 55 for removing labels from said label box to articles to be labeled on said rest, supplemental picker means arranged to close the space between said pickers, a paste roller for applying paste to said pickers and said supplemental picker means, a grip finger and means for opening said supplemental picker means to allow said grip finger to hold the label on the article to be labeled.

60 4. A labeling machine comprising in combination a rest for holding articles to be labeled, a label box, pickers for removing labels from said label box to articles to be labeled on said rest, supplemental picker means arranged to close the space between 70 said pickers, a paste roller for applying paste to said pickers and said supplemental picker means, a grip finger, means for opening said supplemental picker means to allow said grip finger to operate, and means for closing said supplemental picker means to allow said paste roller to operate.

75 5. A labeling machine comprising in combination a rest for holding articles to be labeled, a label box, pickers spaced apart for 80 removing labels from said label box to articles to be labeled on said rest, supplemental picker means arranged to close the space between said pickers, means for hinging said supplemental picker means to the adjacent sides of said pickers, and means 85 secured to said rest for opening and closing said supplemental picker means.

90 6. A labeling machine comprising in combination a rest for holding articles to be labeled, a label box, pickers spaced apart for removing labels from said label box to 95 articles to be labeled on said rest, supplemental pickers hinged to adjacent edges of said spaced pickers, spring means for holding the faces of said supplemental pickers normally flush with said spaced pickers, and means for opening said supplemental pickers against the action of said 100 spring means.

In testimony whereof I have signed this specification in the presence of two subscribing witnesses.

HARRY J. WILLIAMS.
